Primary Examiner — Catherine S Posthauer*Assistant Examiner* — Joan E. Diehl(57) **CLAIM**

The ornamental design for a bottle, as shown and described.

DESCRIPTION

FIG. 1 is a top perspective view of a bottle showing my new design, shown without a lid to show features not seen when lid is in place;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the bottle, shown with lid;

FIG. 10 is a bottom perspective view thereof;

FIG. 11 is a front view thereof;

FIG. 12 is a rear view thereof;

FIG. 13 is a left side view thereof;

FIG. 14 is a right side view thereof; and,

FIG. 15 is a top view thereof.

The broken lines illustrate portions of the article that form no part of the claim.

1 Claim, 14 Drawing Sheets(56)
